UNITED STATES PATENT OFFICE.

JOSEPH A. HALL, JR., AND OTTMAR M. TISHLARICH, OF PITTSBURGH, PENNSYLVANIA, ASSIGNORS TO A. M. BYERS COMPANY, OF PITTSBURGH, PENNSYLVANIA, A CORPORATION OF PENNSYLVANIA.

METHOD AND APPARATUS FOR MARKING ARTICLES.

Application filed September 24, 1924. Serial No. 739,666.

The present invention relates broadly to liquid coating apparatus, and more particularly to a method and apparatus for applying a designating mark to articles of manufacture, such as pipes, rods and the like.

In order to enable the product of one manufacturer to be easily distinguished from that of another, it is desirable, under present trade conditions, to apply certain characteristic marks thereto. The present invention has particularly for its object the application of a spiral stripe to pipes and rods. The invention further has for its object the provision of apparatus for feeding the paint or other coating material to a carrier or applying device, and for keeping the coating material thoroughly mixed and as free from foreign particles as possible.

In the accompanying drawings we have shown, for purposes of illustration only, certain preferred embodiments of the present invention, it being understood that the drawings do not define the limits of the invention, as changes in the construction and operation as disclosed therein may obviously be made without departing from the spirit of the invention or scope of our broader claims.

In the drawings:—

Figure 1 is a top plan view, largely diagrammatic, illustrating one form of apparatus for carrying out the present invention.

Figure 2 is a view similar to Figure 1 illustrating a slightly modified embodiment of the invention.

Figure 3 is a vertical sectional view, partly broken away, on the line III—III of Figure 1, certain of the parts being shown in elevation,

Figure 4 is an end elevation, on an enlarged scale, of a portion of the apparatus,

Figure 5 is a detail sectional view, on an enlarged scale, of a portion of an applying unit,

Figure 6 is a vertical transverse sectional view on a line VI—VI of Figure 3, looking in the direction of the arrows,

Figure 7 is a vertical transverse sectional view similar to Figure 6 illustrating a modified form of the invention,

Figure 8 is a view similar to Figures 3 and 5 and illustrating means for supporting certain of the parts of the applying unit, and

Figure 9 is a view similar to Figure 8, but illustrating a slightly modified form of the invention.

In accordance with the present invention the marking is preferably effected by providing a line of marking material and rolling the article to be marked thereacross with the longitudinal axis of the article maintained at an angle of less than 90° to the axis of the marking line. While this object may be accomplished in a number of different ways, we have found that desirable results may be obtained by providing supports 2, as illustrated in Figure 1, spaced a distance which is substantially equal to the length of the article to be marked whereby the article may be easily supported and rolled thereon during the marking operation. Positioned between the supports 2 is a pot or trough 3 which may, if desired, be constructed in sections, as illustrated, and adapted to contain the coating material.

Suitably journalled at its opposite ends in the end walls of the pot 3 is a carrier 4 adapted to transfer the coating material from the pot to the article. This carrier may conveniently be constructed in the form of a roll which is so mounted that a portion of its periphery at all times projects above the upper edge of the pot and also lies in a plane which is slightly higher than the plane of contact between the supports 2 and the articles. The pot 3 is also so arranged that the axis of the carrier mounted therein intersects the longitudinal axes of the supports 2 to form supplemental angles having different values. By reason of this construction, it will be apparent that if the articles illustrated in the drawings as comprising pipes or rods P are rolled on the supports 2 from the station A to the station B their per-

ripheries will be in contact with a portion of the carrier 4 whereby coating material will be transferred from the carrier to the articles. By reason of the angularity maintained between the carrier and the articles, this material will be transferred to the articles to form a spiral mark or stripe S.

In order to continually provide a sufficient supply of coating material we have 10 found it desirable to rotate the carrier 4. This may be accomplished by providing a transversely extending shaft 5 adapted to be driven at a suitable speed by a motor 6. Secured to the shaft 5 is a pulley 7 adapted 15 to drive a belt 8 passing over a pulley 9 keyed to a shaft 10, as indicated in Figure 5, journalled at its opposite ends in the end walls of the pot 3. This shaft, in addition to serving as a driving means for the carrier, 20 is also adapted to serve as an agitator for maintaining the coating material within the pot in a constant state of agitation, and also for effecting the removal therefrom of heavy foreign particles. These functions may be 25 accomplished by providing the portion of the shaft within the pot with a spiral blade 11 acting upon rotation of the shaft as indicated by the arrow a to produce a movement of the coating material in the direction of the arrow b. Preferably, the edge 30 of the spiral conveyor is in contact with the bottom of the pot whereby any foreign material thereon will be moved lengthwise of the pot and deposited in a collecting chamber 12 provided at one end thereof. This chamber may be formed with a clean- 35 out opening whereby the foreign material may be removed at will, as will be well understood.

40 Intermediate the shaft 10 and the carrier 4 may be provided a second shaft 13 having a construction similar to the construction of the shaft 10, just described. In order, however, to rotate the shafts 10 and 13 in different directions to effect a more thorough agitation of the coating material, the shafts are directly intergeared by means of the gears 14. With the gearing arrangement illustrated, it will be apparent that the shaft 45 10 will be rotated at a higher speed than the shaft 13, thereby tending to prevent any pigment from settling out from the coating material and, at the same time, rotating the intermediate shaft 13 at a speed slow enough 50 to prevent splashing of the coating material over the sides of the pot.

For rotating the carrier 4 there may be 60 provided a gear 15 on the shaft 13 adapted to mesh with a gear 16 which is keyed to the hub of a gear 17 loosely journalled on the shaft 10. The gear 17 in turn meshes with an idle gear 18 on the shaft 13 and through the idle gear drives the gear 19 splined to the carrier shaft. This gear train 65 will preferably be such that the carrier 4

will have a still slower speed of rotation than the shaft 13. The level of the coating material in the pot is maintained high enough so that at least a portion of the carrier dips into the same at all times. During the rotation this coating material will become uniformly distributed over its surface and any surplus will be effectively removed by suitable means, such as doctor blades 20. For convenience in filling the 75 pot as may be required, it may be provided with an off-set 21 as clearly shown in Figures 1 and 6.

The carrier 4 may be constructed in the form of a tube, as indicated in Figure 8, 80 with the ends carried by stub shafts 22 projecting thereinto. To prevent sagging, any desired number of intermediate bearings 23, both for the carrier and for the intermediate shaft, may be provided. In still other cases, 85 the carrier may be constructed of a solid rod, as shown in Figure 7.

In Figure 9, there is disclosed a slightly modified form of the invention, in which the intermediate shaft 13 is omitted entirely, the bottom shaft 10' being relied upon 90 to effect all of the necessary agitation and removal of foreign matter.

In some cases it may be desirable to dispense with the use of a single pot as before 95 described and provide a construction as indicated in Figure 2, in which a plurality of relatively smaller pots 3' are provided. In such an event, the carrier 4' of each pot may have a suitable driving connection 8' 100 with the driven shaft 5'. The angularity of the pots may be varied, if desired, in marking articles of different diameters whereby the individual lines formed by each of the marking devices may come into registration and form a continuous spiral. In other cases the pots may be set at an arbitrary angle and the individual marks formed by each of the carriers relied upon to produce the effect of a continuous spiral. 105

With any form of our invention, the highest portion of the carrier or carriers provided will preferably be slightly above the supporting surface of the supports 2 so that an effective contact between the carriers and 115 the articles is insured.

The advantages of the present invention arise from the provision of a method and apparatus by means of which a spiral may be effectively applied to certain articles of 120 manufacture.

Further advantages arise from the provision of an apparatus having means for maintaining the coating material thoroughly mixed and free from undesirable impurities. 125

We claim:

1. In the method of marking articles, the steps of rotating an article in contact with a coated roll and causing the contacting por- 130

tion of the roll to move along the article while in rolling contact with each other to produce a spiral stripe on the article.

2. In the method of marking articles, the 5 steps of rolling an article over a coating roll while maintaining the axes of the article and roll at an angle to each other to cause the contacting portion of the roll to move along the article during the rotation of the article 10 while passing thereover, to form a spiral stripe on the article.

3. In the method of marking articles, the 15 steps consisting of rolling a cylindrical article over an elongated coating roll having a length materially greater than the width of the mark it is desired to produce, and maintaining the axes of the article and roll at an angle to each other to cause the point of contact between the roll and article to simultaneously travel along both the roll and article to form a spiral stripe on the article.

4. An apparatus for striping cylindrical articles, comprising a runway for the articles, and a striper over which the articles 25 are rolled projecting above the plane of the runway and at an angle of less than 90° to the line of movement of the articles, whereby the point of contact between the articles and the striper is shifted along the article during its movement thereover.

5. An apparatus for striping cylindrical articles, comprising a runway with parallel supports along which the articles to be marked are rolled, and a marker extending 35 above the plane of the supports and at an angle less than 90° to the supports, whereby the line of contact between the articles and marker is moved along the article during the rolling of the articles over the marker.

6. An apparatus for striping cylindrical articles, comprising a runway along which the articles to be marked are rolled, and a marking roller extending above the plane of the 45 runway at an angle less than 90° thereto, whereby the line of contact between the articles and marking roller is moved along the article during the rolling of the articles over the marking roller.

7. An apparatus for striping cylindrical articles, comprising a runway along which the articles to be marked are rolled, a marking roller extending above the plane of the 55 runway at an angle less than 90° thereto, whereby the line of contact between the articles and the marking roller is moved along the article during the rolling of the articles over the marking roller, and means for rotating the roller.

8. Apparatus for marking articles, comprising a plurality of spaced supports, and marking means located therebetween and having its longitudinal axis arranged to intersect said supports to provide supplemental angles of different values, and means 60

for supplying coating material to said marking means.

9. Apparatus for marking articles, comprising a plurality of spaced supports, and a roll located therebetween and having its 70 longitudinal axis arranged to intersect said supports to provide supplemental angles of different values, and means for supplying coating material to said roll.

10. A marking device, comprising in combination 75 a pot for coating material, a transfer carrier in the upper portion thereof, a plurality of means below the carrier for agitating the coating material and providing a uniform mixture for the carrier, and means for operating said means in different directions and at different speeds.

11. In a marking device, a pot for the 80 coating material, a collecting chamber at one end of the pot, means for transferring the coating material from the pot to the article to be coated, and means for conveying foreign material from the pot into said chamber.

12. A marking device, comprising in combination 85 a pot for coating material, a transfer carrier in the upper portion thereof, a plurality of superimposed means below the carrier for agitating the coating material and providing a uniform mixture for the 90 carrier, one of said means cooperating with the bottom of the pot to convey foreign material longitudinally thereof, and means for operating said agitating means in different directions and at different speeds.

13. In the method of marking articles, the 95 steps of rotating an article in contact with a coated roll and causing the contacting portion of the roll to move uniformly along the articles while they are in rolling contact 105 one with the other to produce a spiral stripe on the article.

14. In the method of marking articles, the 110 steps consisting of causing relative movement between a cylindrical article and an elongated coating roll having a length materially greater than the width of the mark it is desired to produce, and maintaining the axes of the article and roll at an angle to each other to cause the point of contact between the roll and article to simultaneously travel along both the roll and article to form a spiral stripe on the article.

15. In the method of marking articles, the 115 steps consisting of causing relative movement between a cylindrical article and a series of elongated coating rolls each having a length materially greater than the width of the mark it is desired to produce, and maintaining the axes of the article and the rolls at angles to each other to cause the points of contact between the roll and article to travel along both the rolls and article to form spiral stripes on the article.

16. In the method of marking articles, the 120 125 130

4
steps consisting of causing relative movement between a cylindrical article and a continuously renewed marker having a length materially greater than the width of the mark it is desired to produce, and maintaining the axes of the article and marker at an angle to each other to cause the point of contact between the marker and article

to simultaneously travel along both the marker and article to form a spiral stripe ¹⁰ on the article.

In testimony whereof we have hereunto set our hand.

JOSEPH A. HALL, JR.
OTTMAR M. TISHLARICH.
